(57) **CLAIM**

The ornamental design for a cup and cell phone holder for armrest, as shown and described.

DESCRIPTION

FIG. 1 is an upper perspective view of a cup and cell phone holder for armrest showing my new design.

FIG. 2 is a front elevation view thereof;

FIG. 3 is a rear elevation view thereof;

FIG. 4 is a side view thereof;

FIG. 5 is an opposite side view thereof;

FIG. 6 is a top plan view thereof;

FIG. 7 is a bottom plan view thereof; and,

FIG. 8 is a perspective view showing the cup and cell phone holder for armrest positioned in an arm of a chair.

The broken line showing of a chair with an armrest in FIG. 8 illustrates the environment of the claimed design and forms no part thereof. The remaining broken lines illustrate portions of the cup and cell phone holder for armrest that form no part of the claimed design.
